RIGHT ANGLED CONNECTION FOR BUILDING ELEMENTS

The invention relates to a connection for building elements arranged at right angles, especially hollow or filled flat building panels, the coverplates of the panels along the edges being provided with joining faces, interconnected by glueing, said joining faces making an angle of 45° with respect to the surfaces of the panels. Such a connection for building elements is e.g. known from French Specification 1.289.484, FIG. 7. In order to obtain the known connection it is necessary to use external metal coverplates in order to prevent sliding movements between said joining faces f.i. during glueing of the connection. As a matter of fact the use of such coverplates means a complication when assembling the parts to be interconnected. Further it is necessary to use grooves in the outer faces of the building panels for locking the edges of the cover plates. The object of the invention consists in the removal of said disadvantages, obtaining at the same time new advantages.

The connection for building elements according to the invention is characterised by complementary interlocking end-profiles along said edges of the coverplates of adjoining panels, each end profile forming part of a panel. In the first place the advantage of a simplified assembling of the building elements is obtained. A further advantage consists in a complete thermal insulation of the connection. The glue connection shows a favourable matching and a self centring action, and is only stressed by shearing forces. Without any difficulty a real hermetically sealing may be obtained.

An efficient embodiment of the invention is characterised in that in transverse section of the connection the edges of the slanting joining face of a first panel are provided with transverse elongations for enclosing the end profile of the other panel.

In many cases it is desirable to have rounded off edges at the exterior of a right angled panel connection. This may be obtained by application according to the invention by transverse elongations of the outer coverplates of two adjoining panels, showing the configuration of cylinders with a common axis, coinciding with the inner edges of the slanting joining faces.

The connection for building elements according to the invention is very suitable for making trihedral connections, which may be obtained by combining two right angled connections according to the invention. For obtaining such trihedral connections according to the invention it is possible to apply straight saw cuts.

The invention covers further a method for making panels or building elements for the above connections. This method is characterised in that each time two complementary end profiles are obtained from a single box profile, said box profile being divided into two complementary end profiles by sawing or a similar treatment along a plane, parallel to the longitudinal direction of the box profile. By starting from a single box profile it is possible to obtain without difficulties complementary end profiles with excellent matching properties, enabling an easy assembling of the connection.

The invention will be further explained by means of the embodiments of the drawings.

FIG. 1 gives a transverse section of a single basic box profile for obtaining two complementary profiles according to the invention.

FIG. 2 gives a transverse section of a right angled connection of building elements according to the invention, the section taken according to the line II-II of FIG. 3.

FIG. 3 gives an isometric view of a trihedral connection according to the invention.

FIG. 4 shows the assembling of the trihedral connection of FIG. 3.

FIG. 1 gives the shape in transverse section of a single box profile, especially manufactured from glass fibre-polyester resin, said profile being divided into sections of suitable length, whereupon the sections are divided into two complementary parts 1 and 2 by a longitudinal saw cut 3. This saw cut is directed in a plane parallel to the longitudinal direction of the profile in such a way, that two complementary end profiles are obtained. The end profiles 1 and 2 are respectively connected to the edges of two building elements or panels 4 and 5, each panel being build up out of flat cover plates 6, 7, 8 and 9. The coverplates are fastened to the end profiles by glueing, rivetting or in any other suitable way. The hollow panels thus obtained may be provided with a filling, e.g. having a cellular structure, a honey comb structure or consisting of foam plastic. Further particulars about such building elements belong to the prior art and are e.g. specified in the above-mentioned French specification.

For obtaining a rigid connection between adjoining panels interengaging surfaces are covered by glue, whereupon the complementary end profiles are brought fully into contact with each other. After hardening of the glue a very strong connection is obtained, providing a hermetic sealing between the interior and the exterior of the panels.

The connection according to the invention enables the use of straight saw cuts.

What I claim is:

1. In a building construction, in combination: first and second building panels fixedly disposed at right angles to each other to form a corner configuration, each panel including inner and outer coverplates and an edge profile member at that edge of the panel adjoining the edge of the other panel to form said corner;

one of said edge profile members having an edge surface disposed at an acute angle to the plane of its associated panel and having inner and outer flanges projecting from said edge surface parallel with and overlapping respective edges of its associated coverplates and being joined thereto;

the other of said edge profile members having an edge surface disposed at an acute angle to the plane of its associated panel and having inner and outer flanges projecting from such edge surface parallel with and overlapping respective edges of its associated coverplates and being joined thereto;

said other edge profile member having inner and outer extension flanges extending from the edge surface thereof to define a laterally facing channel snugly receiving said one edge profile member in straddling relation to said one edge profile member; and

adhesive means joining the inner surfaces of said extension flanges to the marginal edge of that building panel of which said one edge profile member

forms a part so that said edge surfaces of the two profile members are in face-to-face contact.

2. In a building construction as defined in claim 1 wherein the outer flanges of said other edge profile member are arcuate on either side of said edge surfaces and wherein the outer flange of said one edge profile member is complementarily arcuate to conform with the outer arcuate extension flange of said other edge profile member.

3. In a building construction as defined in claim 2 wherein said arcuate flange portions of said one edge profile member form a cylindrical surface portion having a center of curvature lying in a plane substantially coincidental with the edge surface of said other edge profile member.

4. In a building construction as defined in claim 3 wherein each building panel is filled with material between its coverplates.

5. In a building construction as defined in claim 1 wherein each edge profile member is comprised of integrally joined web-like portions of substantially uniform thicknesses.

6. In a building construction as defined in claim 1 including a third building panel arranged in trihedral re-

lation to said first and second building panels, the adjacent edges of all three building panels being joined by adhesive means acting between edge profile members as aforesaid.

5 7. In a building construction as defined in claim 6 wherein each edge profile member is comprised of integrally joined web-like portions of substantially uniform thicknesses.

10 8. In a building construction as defined in claim 7 wherein the outer flanges of said other edge profile member are arcuate on either side of said edge surfaces and wherein the outer flange of said one edge profile member is complementarily arcuate to conform with the outer arcuate extension flange of said other edge profile member.

15 9. In a building construction as defined in claim 6 wherein the outer flanges of said other edge profile member are arcuate on either side of said edge surfaces and wherein the outer flange of said one edge profile member is complementarily arcuate to conform with the outer arcuate extension flange of said other edge profile member.
